United States Patent Office.

GIDEON W. COLE, OF CANTON, ILLINOIS.

Letters Patent No. 98,231, dated December 28, 1869.

IMPROVEMENT IN PLANING-MACHINE.

The Schedule referred to in these Letters Patent and making part of the same.

To all whom it may concern:

Be it known that I, GIDEON W. COLE, of Canton, in the county of Fulton, and State of Illinois, have invented a new and useful Improvement in Planing-Machines; and I do hereby declare that the following is a full, clear, and exact description of the construction and operation of the same, reference being had to the annexed drawings, making a part of this specification, in which—

Figure 1 is a perspective view.

Figure 2 is a view of the under side of the machine, showing parts not exhibited in fig. 1.

This invention relates to certain improvements in planing-machines, and consists in the peculiar construction and arrangement of a tilting or oscillating top, which is provided with an adjustable section, as will be fully described hereafter.

A, in fig. 1, is the "oscillating top-bed," held in a horizontal position by means of springs and rods underneath, as hereinafter more fully described.

B, in fig. 1, is a section of the top-bed, held in its place by a spring, I, in fig. 2, and regulated by thumb-screws J J J, to cut any thickness of shaving required.

C, in fig. 1, is an adjustable guide, for planing square or bevel edges.

D D are used to make the top-bed stationary, if desired, by means of thumb-screws E E, in fig. 1.

F F are the side frames.

G, in fig. 1, is the boxing, through which the shaft passes, to which is attached the planer.

H H, in fig. 2, are projections of the boxing on the inside of the frame, on which rests the oscillating top-bed.

To enable others skilled in the art to make and use my invention, I will proceed to describe its construction and operation.

I construct the frames F F of iron, placed upon a suitable foundation to give it the required height, with circular iron boxing in the centre, through which passes the shaft that runs the planer, and projecting inward sufficiently for the top-bed to rest upon.

I construct my "oscillating top-bed" of iron, with circular bearings, to rest upon the circular boxings above described, with the points extending perpendicularly a short distance below the centre of the boxings, so as to be kept in its proper place when raised by set-screws.

I construct the section of the top-bed B in a separate piece, so it can be raised by the thumb-screws to regulate the thickness of the shaving, it being held to its place by a spring and thumb-screw, I, fig. 2. Said spring I make of flat steel, and fit the ends into gains in sides of top-bed, and attach it to section B, by thumb-screw, in its centre.

I construct a set-screw, N, and a corresponding one on the opposite side, with the points of said screws resting on the top of the circular boxing, by means of which the top-bed is adjusted to the planing-bits.

I construct a guide, C, fig. 1, of the same length of top-bed, with end-pieces attached thereto, which are pivoted at L, and corresponding pivot at opposite end.

I construct a slot in end-piece, describing part of the arc of a circle, with pivot L for its centre, through which passes a screw, M, by which the guide is kept in any desired position.

I construct two springs, K K, fig. 2, attached to the lower side of frame by a screw in the centre of each, the ends being curved downward and inward, and connected by rods to the top-bed, by which it is kept in a horizontal position, except as the springs will admit of its oscillating when at work.

The object of the oscillating movement of the top-bed is for the better accommodation of itself to the work of planing long timber or lumber, so that if it is not kept perfectly level, the top-bed will play up and down with the piece being planed, and still keep in its relative position with the planing-knives, working in the opening in the centre of the top-bed.

By the use of a rest, a little in advance of the machine, one hand can work it as easily as two hands can with the stationary bed, and do the work much better.

What I claim as my invention, and desire to secure by Letters Patent, is—

The oscillating top-bed A, having the adjustable section B and slotted side frame D, when all the parts are constructed, arranged, and operated substantially as described, and for the purpose set forth.

GIDEON W. COLE.
